US00D527163S

(12) United States Design Patent (10) Patent No.: US D527,163 S
Walsh et al. (45) Date of Patent: * Aug. 29, 2006

(54) EXTRUDED CONFECTION

(75) Inventors: Michelle K. Walsh, Steamwood, IL (US); Michael J. Feilen, Wheaton, IL (US)

(73) Assignee: QA Products, Inc., Elk Grove Village, IL (US)

() Term: 14 Years

(21) Appl. No.: 29/232,565

(22) Filed: Jun. 21, 2005

(51) LOC (8) Cl. 01-01

(52) U.S. Cl. D1/115; D1/120; D1/127

(58) Field of Classification Search D1/106, D1/115, 120, 126-129; D1/48, 63, 81, 120, D11/139; 426/96, 104, 143, 440, 445, 449-50, 426/514-5, 621, 625, 658, 660

(57) CLAIM

We claim the ornamental design for an extruded confection, as shown and described.

DESCRIPTION

FIG. 1 is a perspective view of an extruded confection of the present invention;

FIG. 2 is a front side view thereof;

FIG. 3 is a back view thereof;

FIG. 4 is a top view thereof;

FIG. 5 is a left side view thereof;

FIG. 6 is a right side view thereof; and,

FIG. 7 is a bottom view thereof.
